DESIGN FOR A LID OF A BOX OR THE LIKE

André Melin, Paris, France, assignor to Parfumerie Roger et Gallet, Société Anonyme, Paris, France, a corporation of France

Application April 1, 1933, Serial No. 47,668

Term of patent 14 years

To all whom it may concern:

Be it known that I, ANDRÉ MELIN, a citizen of the Republic of France, residing at 30, Quai du Louvre, Paris, France, have invented a new, original, and ornamental Design for Lid of a Box or the like, of which the following is a specification, reference being had to the accompanying drawing, forming part thereof.

Fig. 1 is a top plan view of a lid of a box or the like, showing my new design; and Fig. 2 is a perspective view thereof.

I claim:

The ornamental design for a lid of a box or the like, as shown.

ANDRÉ MELIN.
